US00D533045S

(12) **United States Design Patent** (10) **Patent No.:** **US D533,045 S**
(45) **Date of Patent:** **** Dec. 5, 2006**

(54) **LOCKING OR CLOSING DEVICE**

(75) Inventor: **Carl-Jürgen Schroth**, Soest (DE)

(73) Assignee: **Schroth Safety Products GmbH**,
Arnsberg (DE)

(**) Term: **14 Years**

(21) Appl. No.: **29/232,281**

(22) Filed: **Jun. 16, 2005**

(30) **Foreign Application Priority Data**

Dec. 28, 2004 (EM) 000272398-0001

(51) **LOC (8) Cl.** **08-06**

(52) **U.S. Cl.** **D8/300**

(58) **Field of Classification Search** D11/200-216,
D11/218; D2/639; D8/300, 310; 24/196,
24/303, 633, 634, 639, 642, 650; 280/801.1;
180/268, 270; 340/457.1

See application file for complete search history.
